US00D642747S

(12) **United States Design Patent**
Marschke et al.

(10) **Patent No.:** **US D642,747 S**
(45) **Date of Patent:** **** Aug. 2, 2011**

(54) **PET COLLAR**

(76) Inventors: **Jacqueline K. Marschke**, Tucson, AZ (US); **Daniel H. Marschke**, Tucson, AZ (US)

(**) Term: **14 Years**

(21) Appl. No.: **29/350,772**

(22) Filed: **Nov. 23, 2009**

(51) **LOC (9) Cl.** **30-04**

(52) **U.S. Cl.** **D30/152**

(58) **Field of Classification Search** ..... D30/151–155, D30/144, 199, 160; 119/792–798, 850, 855–859, 119/863–865, 654, 905, 907, 815, 712, 802, 119/784, 769, 760, 776, 862; 242/381.1–381.2, 242/385.4, 378.3, 376.1, 385.1, 916, 601, 242/570, 405, 404, 371, 223, 170, 388.1, 242/405.2, 377, 381.3, 381.6, 405.3, 388.6, 242/384.7, 382, 396.1, 404.1, 380; 362/108; 33/767, 769, 414; D12/400; D3/229, 230, D3/207, 208, 215; 40/1.5, 455, 640, 303; 206/63.3, 459.5, 702, 408; D6/515; D8/358, D8/360, 347, 360.1, 359, 356, DIG. 1; D24/145; D10/57, 104, 72; D20/28; 224/666, 678; 16/445; 283/74, 70; D11/232, 200, 216, D11/1, 2, 86, 87, 201, 206–210, 212–215, D11/218; 24/163 K, 122.3, 323, 702, 600.4–600.7, 24/163 R, 169–171, 173, 177–179, 191, 194, 24/195, 197, 200, 303, 616, 635, 313, 615, 24/3, 6, 3 K, 599.2, 96, 221, 237, 311, 312, 24/314, 321, 338, 339, 309; 428/3, 4; 54/76; 63/29.1, 3; 191/12.2 R, 12.4; D13/154, D13/153, 137.4, 155; D19/69, 67; 379/438; 446/26; 473/576; D22/140; 174/135; 439/504, 439/13, 501; D34/33; 188/83, 82.1, 65.1; 254/134.3 FT; D29/124; D2/627, 624, 633, D2/625; 132/145, 146, 148; 2/314; 59/79.1
